UNITED STATES PATENT OFFICE.

WILLIAM H. HUNT, OF NATIONAL CITY, CALIFORNIA.

GAS-ENGINE CRANK-CASE-CHARGING DEVICE.

1,360,217.

Specification of Letters Patent. Patented Nov. 23, 1920.

Application filed June 19, 1917. Serial No. 175,603.

To all whom it may concern:

Be it known that I, WILLIAM H. HUNT, a citizen of the United States, residing at National City, in the county of San Diego and State of California, have invented certain new and useful Improvements in Gas-Engine Crank-Case-Charging Devices, of which the following is a specification.

My invention relates to a device of this class with the crank case of a gas engine for forcing the gas into the crank case at intervals and the objects of my invention are: first, to provide means for producing increased carburetor action and a better mixture of the fuel and air by reason of the high velocity of the gas from the carburetor to the crank case; second, to provide a device of this class which will relieve the piston of the duty of drawing in the new charge whereby the crank case volume need not be unduly reduced; third, to provide a device of this class which will equalize the crank case compression to suit any engine speed thereby making it possible to transfer a full charge of gas to the working cylinder at any engine speed; fourth, to provide a device of this class which may be constructed to supply a charge of gas in any proportion of the piston displacement desired; fifth, to provide a device of this class by the use of which it will be possible to procure a full cylinder of gas at each suction stroke; and sixth, to provide a device of this class which is very simple and economical of construction, durable, easy to operate and is applicable to the different makes of engine crank cases and will not readily deteriorate or get out of order.

With these and other objects in view as will appear hereinafter, my invention consists of certain novel features of construction, combination and arrangement of parts as will be hereinafter described in detail and particularly set forth in the appended claims, reference being had to the accompanying drawings and to the characters of reference thereon which form a part of this specification in which:

Figure 1 is a sectional view of a crank case showing my device in connection therewith, and showing by dotted lines the varying position of the charging member; Fig. 2 is a sectional view thereof at a right angle to that of Fig. 1; and Fig. 3 is a front elevational view of the crank case with my device in position thereon.

Similar characters of reference refer to similar parts throughout the several views.

The crank case 1, auxiliary crank shaft 2, connecting rod 3, plunger 4, valve 5, valve 6, 60 casing extension 7, plate 8, support 9, cylinder 10, and main crank shaft 11 constitute the principal parts of my structure.

The crank case 1 is similarly shaped to the conventional crank case, except the portions which are changed for the application of my device thereto as will be hereinafter described and I have herein, illustrated the same for a one cylinder 2 cycle gas engine. This crank case is provided with the bearings 1^a adapted for the main shaft 11 which is revolubly mounted therein. In the upper portion of said casing 1 and extending inwardly and outwardly from the wall of said casing is the bearing 1^b in which is revolubly 75 mounted a small auxiliary crank shaft 2. Its opposite end is supported by the bearing 1^c which is secured to the case 1 by bolts 1^d. Said crank shaft 2 extends outwardly through the crank case on one side and on 80 the outwardly extending end is secured a spur gear 2^a and mounted on the main crank shaft 11 is another spur gear 11^a with which the spur gear 2^a meshes thereby turning the shaft 2 with the revolution of the main crank 85 shaft 11. Mounted on this crank shaft 2 is one end of the connecting rod 3 and its other end is pivotally connected to a lug 4^a near the upper side of the plunger 4. This connecting rod 3 consists of two bars 3^a and 3^b 90 spacing apart from each other a sufficient distance to permit the main connecting rod of the engine free movement between said bars. Mounted on the one side of said crank case and secured thereto by bolts 7^a is the 95 extension portion of the crank case 7 and made tight by means of gasket 7^b. This extension 7 is wide at its upper side and narrow at its lower side. The lower side comprising a semi-circular member 9 in which is 100 pivotally mounted the lower side of the plunger 4. The upper side of this casing extension 7 is curved on the radius from the center of the pivotal mounting of the plunger 4 so as to provide a fit of the plunger 4 in its 105 movement back and forth in said extended portion. This plunger is provided in its upper and side edges with a packing member 4^b and with compression springs 4^c mounted in holes therein and engaging the back 110 surface of the said packing member 4^b. Mounted centrally in this plunger 4 is a

valve 5 which is held closed by means of a flat spring 5^a secured thereto and secured to the plunger 4 thus providing a valve which is opened by pressure and closed by the 5 spring when the pressure is relieved. Secured to the face of said extended portion 7 is the plate 8 by means of bolts 8^a and provided with gaskets 8^b for providing a tight fit. Mounted on the outer side of this plate 10 8 is an extension 8^c provided with a flange 8^d which is adapted for the connection of the carbureter. Mounted in this plate, communicating with the hole in the extension 7 to the carbureter is a valve 6 which is held closed by means of a plate spring 6^a thereby providing a valve which is held closed by the 15 spring and opened by pressure. The crank case communicates with by-passes 10^a leading to the intake of the cylinders.

20 Though I have shown and described a particular construction, combination and arrangement of parts, I do not wish to be limited to this particular construction, combination and arrangement but desire to include in the purview of my invention the construction, combination and arrangement substantially as set forth in the appended claims.

It is obvious that with this construction 30 there is provided a plunger which is pivotally mounted at its lower side and adapted to swing on said pivot in the extension 7 and made tight by the packing 4^b. That with the revolution of the main shaft 11, the 35 auxiliary shaft 2 will revolve which in turn will move the plunger 4 backwardly and forwardly at its upper side. That when the plunger 4 moves inwardly toward the crank case the valve 5 will be closed, compressing 40 the gas in the crank case and forcing it into by-pass 10^a at the same time a vacuum will be caused between the plunger 4 and the plate 8 from the carbureter and in the outward movement of said plunger 4 the valve 45 6 will be closed and the valve 5 opened, causing the gas between said plunger 4 and the plate 8 to enter the crank case.

Having thus described my invention what 50 I claim as new and desire to secure by Letters Patent is:

1. In a device of the class described the combination with a crank case and main crank shaft, of an extended portion secured to one side of said crank case, a plunger reciprocally mounted at one side thereof in said extended portion, a valve mounted in said plunger, a valve mounted in the outer side portion of said extension and means connected with the main shaft of the engine for reciprocating said plunger.

2. In a device of the class described, the combination with a gas engine crank case and main crank shaft of an extending portion secured to one side of said crank case communicating internally therewith, a plunger

reciprocally mounted in said extended portion, an inlet valve mounted in said extended portion, an outlet valve communicating therewith and with said crank case and means in connection with said plunger, actuated by the main shaft of the engine for reciprocating said plunger. 70

3. In a device of the class described, the combination with a gas engine crank case and main crank shaft, of an extending portion secured to one side of said crank case communicating internally therewith, a plunger reciprocally mounted in said extended portion, a valve mounted in said plunger, a valve mounted in the inlet to said extended portion and means in connection with said plunger, actuated by the main shaft of the engine for reciprocating said plunger. 75

4. In a device of the class described, the combination of a gas engine crank case, a main crank shaft mounted therein, a plunger fitting the one side of said crank case pivotally mounted at one of its sides adapted to swing inwardly and outwardly over a portion of interior of said crank case, a carbureter, a valve mounted in said plunger, a valve in the communication between the carbureter and said valve in the said plunger and means connecting said plunger with the main shaft of the engine for operating said plunger. 80

5. In a device of the class described, the combination of a gas engine crank case, a crank case mounted therein, a plunger fitting the one side of said crank case pivotally mounted at one of its sides adapted to swing inwardly and outwardly over a portion of interior of said crank case, a carbureter, a valve mounted in said plunger, a valve in the communication between the carbureter and said valve in the said plunger and means connecting said plunger with the main shaft of the engine for operating said plunger, comprising an auxiliary crank shaft revolvably mounted in said crank case gears mounted on said auxiliary shaft and on the main engine shaft meshing with each other and a connecting rod with one end pivotally mounted on said auxiliary crank shaft and its other end pivotally connected to said plunger. 95

6. In a device of the class described, the combination of a carbureter, a crank case provided with an extended portion on one side communicating with the carbureter, a crank shaft mounted in said crank case, a valve mounted in said crank case at said extended portion, a plunger pivoted at one side and adapted to move back and forth at its opposite side, a valve mounted in said plunger and means connected with the main shaft of the engine for moving the free side of the plunger back and forth. 110

7. In a device of the class described, the 120

combination of a carbureter, a crank case provided with an extended portion on one side communicating with the carbureter, a crank shaft mounted in said crank case, a 5 valve mounted in said crank case at said extended portion, a plunger pivoted at one side and adapted to move back and forth at its opposite side, a valve mounted in said plunger and means connected with the main 10 shaft of the engine for moving the free side of the plunger back and forth, comprising

an auxiliary crank shaft revolvably mounted in said crank case gears mounted on said auxiliary shaft and on the main engine shaft meshing with each other and a connecting 15 rod with one end pivotally mounted on said auxiliary crank shaft and its other end pivotally connected to said plunger.

In testimony whereof, I have hereunto set my hand at San Diego, California this 14th 20 day of June, 1917.

WILLIAM H. HUNT.
